UNITED STATES PATENT OFFICE.

GÉZA SZIKLAI, OF BUDAPEST, AUSTRIA-HUNGARY.

ROWING-CRAFT INTENDED FOR AN AMUSEMENT DEVICE.

1,155,381.

Specification of Letters Patent.

Patented Oct. 5, 1915.

Application filed September 8, 1913. Serial No. 738,675.

To all whom it may concern:

Be it known that I, GÉZA SZIKLAI, a subject of the King of Hungary, residing at Katona Jozsef utca 21, Budapest, VII, in the Empire of Austria-Hungary, have invented a certain new and useful Improvement in Rowing-Craft Intended for an Amusement Device, of which the following is a specification.

10 The present invention relates to a rowing craft intended for the entertainment of people which after the manner of suspension railways, runs upon an upper rail track and is propelled by means of oars bearing 15 in the known manner, against projections or within recesses provided along the track.

In the accompanying drawing, two constructions of the craft are illustrated.

Figure 1 shows a construction with two 20 rails and Fig. 2 shows a modified construction with one rail.

A car *a* of any construction, comprising one or more stationary seats *b* which, after the manner of rowing boats, may be adapted 25 to slide or roll to and fro upon rails, is provided with rowlocks *c* so that a person sitting upon the seat *b* can operate the oars *d* in the usual manner employed in connection with boats. Teeth *f* or the like projections 30 or recesses are provided along the track and on either side of the car, at regular intervals, said teeth constituting points of support for

the oars so that the latter propel the car very rapidly by bearing against these teeth or the like.

The car *a* as shown in Fig. 1, is suspended from a four-wheeled car *g*, running upon two rails arranged above the track, while in the construction shown in Fig. 2, the car *a* is suspended from a two-wheeled car *h* running upon only one rail arranged above the track. The car *a* may naturally be mounted on springs *i* in order to avoid the unpleasantness caused by the vibrations.

What I claim and desire to secure by Letters Patent of the United States is:—

In combination, an upper track, wheels mounted on said track, a boat structure suspended in a freely rotatable manner from said wheels, springs on which said boat structure is mounted, a lower track, two rows of abutments on said lower track, rowlocks, and oars fitting in said rowlocks and adapted frictionally to engage said abutments to propel the boat and by means of such suspension to produce a natural gliding and rocking motion, substantially as herein described.

In testimony whereof I affix my signature in presence of two witnesses.

GÉZA SZIKLAI.

Witnesses:

ARTHUR LÀSBLÉY,
MARIE WEISS.
